[57] ABSTRACT

An automatic device for feeding loop-shaped wire clamps for application to the necks of bottles of wine, champagne, and the like. The device includes a chute for holding a nested pack of wire clamps and means for individually separating the leading clamp from the pack and a magnetic arrangement for carrying and depositing the same in a receptacle whereby the wire clamp can be automatically removed for application to the bottle.

FIG. 4a

AUTOMATIC WIRE CLAMP FEEDING DEVICE FOR BOTTLES

The present invention relates to an automatic wire clamp feeding device for use in bottling plants, such as wineries.

Heretofore, the procedure followed in bottling plants for wine or the like was to manually pick up and apply each wire clamp in a nest on a rotary index table. Obviously, this was costly since it required the use of an operator. The present invention has overcome this disadvantage of the prior art by making this step in wine production automatic and compatible with the automatic transport of wire clamps and the automatic application of each wire clamp to each bottle. Moreover, there is not only a cost saving factor in the present invention but an increase in the production rate.

It is an object of the present invention to provide a simplified wire clamp feeding device which can be inexpensively constructed, and that can be easily incorporated in wineries or other bottling plants in order to reduce the cost of production and at the same time increase the production rate of the plant.

A further object of the present invention is to provide a compact wire clamp feeding device that takes up less space than previously known wire-loop making and applying machines.

An object of the present invention is to provide a stepped delivery chute whereby the leading wire clamp is separated from the pack and may be individually transported to its transfer position.

A further object of the present invention is to provide a magnetic holding and carrier arrangement for separating the leading wire clamp from the stack of clamps.

Another object of the present invention is to provide a stop or escapement device which when in the hold back position prevents the remainder of the stacked pack of wire clamps from being released from the delivery chute after the leading wire clamp is engaged by said magnetic holding and carrier arrangement.

The invention will now be more fully described with reference to the accompanying drawings wherein:

FIG. 1 is a top plan view of the automatic wire clamp feeding device for bottles constructed in accordance with the teachings of the present invention.

FIG. 2 is a side elevational view of the device illustrated in FIG. 1.

FIG. 3 is a perspective view of a plurality of nested wire clamps.

FIG. 4 is a front elevational view of the part carrier showing the magnetic elements therein.

FIG. 4a shows a vertical cross sectional view of the magnetic carrier.

DESCRIPTION OF THE PREFERRED EMBODIMENTS OF THE INVENTION

The present automatic feeding device for bottle wire clamps comprises a support plate 10 with a delivery chute 12 mounted thereon having steps 12a and 12b. A stacked pack of loop-shaped wire clamps 18 are adapted to be positioned on the chute 12, and transported to the chute by means of a vibratory feeder 9 (not shown), the latter forming no part of the present invention. The chute sides 14 have mounted thereon a hold-back and release spring 16 having a free end that terminates in a laterally disposed resilient hold-back finger 20, only one of which is shown. It will be noted that the finger 20 is located in a position to engage a front edge

of the leading wire clamp 18a and thereby hold back the stacked pack (full line position of FIG. 1). Furthermore, the step 12b of the delivery chute 12 permits the leading wire clamp 18a to drop down slightly from the remainder of the pack and separate therefrom so that the same can be easily removed automatically from the chute 12, as will be fully explained hereinafter. The loop-shaped wire clamps 18 are of the type commonly employed with corks of wine and champagne bottles in order to effect a complete sealing of the liquid contents of the bottles. As seen in FIG. 2, the wire clamps 18 in the pack are nested with cork-engaging parts 19 in upright positions.

A cylinder support arm 22 is provided with mounts 24 for a double acting cylinder 26. The piston 28 of the cylinder 26 has a piston rod 30 which is secured at the free end thereof to a movable part carrier 32. FIG. 4 illustrates the part carrier having spaced permanent magnets 34 on the face thereof, as well as spaced openings 36 therethrough which are aligned with push-off pins 38 that are rigidly fixed to an upstanding part 22a of the arm 22. A cam finger 40 is provided on the carrier 32 which is adapted to cam the hold back finger 20 to the release position shown in the dotted line position of FIG. 1 when the part carrier 32 moves to a position whereby the magnets 34 attract the leading wire clamp 18a, as shown in dotted lines in FIG. 1.

After the leading wire clamp 18a has been released from the hold back finger 20 and has been magnetically attracted to the magnets 34 on the movable part carrier 32, the latter moves in the direction of the arrows X. At point Z of this movement of the carrier 32, the push-off pins 38 project through aligned openings 36 and break the magnetic hold of the magnets 34 on the wire clamp 18a thereby permitting the clamp to fall by gravity into a nest or container 42 (FIG. 2). The nest forms no part of the present invention but has the function to automatically transport each of the wire clamps 18 to a station for inserting each of the clamps over the top of the bottles.

What I claim is:

1. An automatic wire clamp feeding device for corked bottles comprising means for delivering a pack of wire clamps to a station, means for separating the leading wire clamp from the remainder of the pack, a reciprocating movable carrier for transporting individual wire clamps from a first position adjacent to said leading wire clamp to a second position for deposit of said clamp, said carrier being provided with openings therethrough, means to hold back said pack as said movable carrier moves to said first position, means on said movable carrier for disengaging said hold back means and magnetic means on said carrier for engaging and holding said leading wire clamp when said carrier is located in said first position, said movable carrier thereafter transporting said leading wire clamp to said second position, and means at said second position for disengaging said leading wire clamp from said carrier which are elements that project through said openings when said carrier is in said second position to push said leading wire clamp out of engagement with said magnetic means.

2. An automatic wire clamp feeding device as claimed in claim 1 wherein said means for delivering said pack of wire clamps to said station is a chute.

3. An automatic wire clamp feeding device as claimed in claim 2 wherein said means for slightly sepa-

rating said leading wire clamp from the remainder of said pack is a step in said chute.

4. An automatic wire clamp feeding device as claimed in claim 1 wherein said means to hold back said pack is a resilient finger that engages the face of the leading wire clamp of the pack.

5. An automatic wire clamp feeding device as claimed in claim 4 wherein said means on said movable

carrier for disengaging said resilient finger is a cam finger.

6. An automatic wire clamp feeding device as claimed in claim 1 further comprising a double acting cylinder provided with a piston having a piston rod, the latter being connected to said movable carrier for moving the same linearly.
